UNITED STATES PATENT OFFICE.

JOHN A. LUNDEM, OF CHICAGO, ILLINOIS, ASSIGNOR OF ONE-HALF TO ROBERT C. DANLY, OF CHICAGO, ILLINOIS.

SOUND BOX.

Application filed January 9, 1922. Serial No. 527,915.

To all whom it may concern:

Be it known that I, JOHN A. LUNDEM, a citizen of the United States of America, residing at Chicago, in the county of Cook 5 and State of Illinois, have invented certain Improvements in Sound Boxes, of which the following is a specification.

This invention relates to that type of sound boxes for phonographs and like sound 10 producing instruments in which the needle or stylus mounting is connected to the sound producing diaphragm by an angularly disposed bar and is pivotally mounted on the sound box casing, and the present improve- 15 ment has for its main object:—

To provide a structural formation and association of parts in a stylus mounting whereby a simple and durable pivotal attachment to the sound box casing is at- 20 tained, in which the vibration of the needle or stylus is effectively confined to a single plane without interference to free vibration in such plane, and with which lost motion or play at the point of pivotal connection is 25 effectively prevented as well and any tendency to movement of the parts under either side or torsional stresses is resisted in an efficient manner, all as will hereinafter more fully appear.

30 In the accompanying drawings:—

Fig. 1 is a central sectional elevation of a sound box illustrating the preferred arrangement of parts in the present invention.

Fig. 2, is an inverted plan view of the 35 same.

Fig. 3, is a front elevation with parts in section on line 3—3, Fig. 2.

Fig. 4, is a detail side elevation illustrating the pivotal connection of the parts.

40 Fig. 5, is a detail perspective view of the stylus mounting parts in a detachable condition.

Fig. 6, is a side elevation of a modification showing the arrangement of parts in connection with an ordinary upright type of 45 sound box.

Like reference numerals indicate like parts in the several views.

Referring to the drawings, 1 designates 50 the sound box casing having the usual tubular tone or outlet neck 2 of the ordinary angularly curved form, by which the sound box casing is revolvably mounted on the end of the tone arm 3 of a phonograph or the 55 like, with the adjustment of parts limited

by a pin 4 on one part moving in an elongated curved slot in the wall of the other part as shown in Fig. 1. This feature is usual to many phonographs and permits of an adjustment of the stylus carrying means 60 for playing either the laterally or the perpendicularly undulating type of records as well as attain an adjustment of the plane of movement of the needle or stylus from the normal right angle relation to the laterally 65 undulating record groove to a greater or less obliquity in an adjustment to attain the desired tone from a particular sound record.

6 designates the sound producing dia- 70 phragm, peripherally mounted in the open face of the sound box casing by annular holding rings 7 of yielding material, or by any other means of attachment usually employed for the purpose.

8 designates the stylus carrying post or 75 stem provided with the usual receiving socket or orifice for the needle or stylus 9, with a lateral thumb screw 10 by which the stylus 9 is detachably secured in said socket and with a lateral bar or arm 11 extending 80 to and attached in any usual manner to the center of the diaphragm 6. In the present improvement the post or stem 8 is provided at the end opposite to its socket or orifice with a lateral plate extension 12 integrally 85 formed with the post or stem, or otherwise fixedly attached thereto. The other end of the plate extension 12 is formed with an orifice for the passage of a binding screw 13 by which said plate extension is rigidly at- 90 tached to a side extension or lug 14 of the sound box casing 1, as shown more particularly in Figs. 1 and 2, and in the preferred construction shown, the outer end of the lug 14 is formed with a depending rib 95 14' the under face of which affords bearing for the end of the plate extension 12 and provides clearance between the main portion of such plate extension and the adjacent face of the sound box casing.

In the present improvement the plate ex- 100 tension 12 constitutes the resilient pivotal connection between the sound box casing and the stylus mounting to permit of the normal vibration of said stylus mounting in actual 105 use. In connection therewith any tendency to undue lateral swing of the stylus mount- 110 ing, with a twisting action on the plate ex- tension 12, is prevented by the following ar- rangement of parts:—

- 15 designates side wings of the flat web form shown, extending upwardly in opposite directions from the sides of the stylus carrying post or stem 8, with their upper ends 5 in transverse spaced relation to the plate extension 12 aforesaid, and with said upper ends formed with bends 16 of the open hook shape as shown and adapted for rocking or pivotal engagement with the hereinafter de-
10 scribed complementary ridges associated with the sound box casing 1.
- 17 designates a crescent shape plate having at its mid-length an orifice for the passage of the binding screw 13 aforesaid, and by 15 which it is attached to the underside of the plate extension 12 and preferably in spaced relation thereto by means of an intermediate washer or spacing plate 18, as shown in Fig. 1.
- 20 19 designates upturned bearing ridges formed on the ends of the plate 17 aforesaid, and having transverse spaced relation corresponding with that of the knuckles 16 of the wings 15 of the stylus carrying post and 25 adapted for interengagement therewith and form a loose rocking pivotal connection for the parts.
- The associated bends 16 and bearing ridges 19 have no part in the normal vibratory movement of the stylus mounting to 30 operate the sound producing diaphragm, and are intended solely to prevent undue lateral vibration of the stylus mounting. In consequence the fit between said bends and ridges 35 is preferably a loose one, as indicated by extended experimental use of the appliance, and with a view to prevent rattle or noise between the parts a cushioning means as follows is employed:—
- 40 20 designates layers of fabric of a woven or other nature secured to the under face of the side extensions or lugs 14 of the sound box casing 1 and adapted to have bearing against the upper surfaces of the bends 16 to 45 hold the same in associated relation to the companion ridges 19 and prevent or dampen any noise or chatter at the points of pivotal connection during actual use.
- 21 designates stop lugs or pins depending 50 from the under side of the sound box casing 1 in adjacent relation to the inner sides of the lateral wings 16 of the stylus carrying post 8 and adapted for contact therewith to properly position the parts in an assembly of 55 the mechanism, as well as to prevent any accidental lateral shifting after assemblage.
- Having thus fully described my invention, what I claim as new and desire to secure by Letters Patent, is:—
- 60 1. In combination, a sound box casing carrying a diaphragm, a stylus carrying post having a fixedly attached angularly arranged resilient plate extension at one end and an angularly arranged bar intermediate
- of its length and operatively connected to the 65 diaphragm, and means for fixedly attaching an end of said resilient plate extension to the sound box casing, the stylus carrying post being provided with oppositely extending lateral wings having bearing engagement 70 with a fixed part of the sound box casing to resist lateral vibration of the stylus carrying post.
2. In combination, a sound box casing carrying a diaphragm, a stylus carrying post 75 having a fixedly attached angularly arranged resilient plate extension at one end and an angularly arranged bar intermediate of its length and operatively connected to the diaphragm, and means for fixedly attaching an end of said resilient plate extension to the sound box casing, the same comprising a transversely arranged confining plate and an attaching screw, the stylus carrying post being provided with oppositely extending lateral wings having bearing engagement 80 with the ends of the aforesaid confining plate by inter-engaging bend and ridge formations.
3. In combination, a sound box casing carrying a diaphragm, a stylus carrying post having a fixedly attached angularly arranged resilient plate extension at one end and an angularly arranged bar intermediate of its length and operatively connected to the diaphragm, means for fixedly attaching 90 an end of said resilient plate extension to the sound box casing, the stylus carrying post being provided with oppositely extending lateral wings having bearing engagement with a fixed part of the sound box casing to resist lateral vibration of the stylus carrying bar, and depending pins on the sound box casing having bearing contact with opposed faces of the lateral wings 100 aforesaid, to position the parts.
4. In combination, a sound box casing carrying a diaphragm, a stylus carrying post having a fixedly attached angularly arranged resilient plate extension at one end 110 and an angularly arranged bar intermediate of its length and operatively connected to the diaphragm, means for fixedly attaching an end of said resilient plate extension to the sound box casing, the same comprising a transversely arranged confining plate and an attaching screw, the stylus carrying post being provided with oppositely extending lateral wings having bearing engagement 115 with the ends of the aforesaid confining plate by inter-engaging bend and ridge formations, and depending pins on the sound box casing having bearing contact with opposed faces of the lateral wings aforesaid to 120 position the parts.
- Signed at Chicago, Illinois, this 31st day of December, 1921.
- JOHN A. LUNDEN.
